UNITED STATES PATENT OFFICE.

DANIEL S. WAUGH, OF DENVER, COLORADO, ASSIGNOR TO THE DENVER ROCK DRILL AND MACHINERY COMPANY, OF DENVER, COLORADO.

HAMMER-DRILL.

No. 919,270.

Specification of Letters Patent.

Patented April 20, 1909.

Application filed July 20, 1906. Serial No. 327,018.

To all whom it may concern:

Be it known that I, DANIEL S. WAUGH, a citizen of the United States, residing in the city and county of Denver and State of Colorado, have invented certain new and useful Improvements in Hammer-Drills; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 The present invention relates to hammer drills, and more particularly to the valve mechanism for controlling the supply and exhaust of the motive fluid to and from the cylinder member.

20 It will be obvious that the invention is not necessarily limited to drills, but may be employed for pneumatic or motive fluid hammers generally.

In the accompanying drawings:—Figure 1 is a longitudinal sectional view through a hammer, showing the novel mechanism. Fig. 2 is an enlarged sectional view through the rear portion of the same, illustrating the position of the valve during the exhaust. Fig. 3 is a similar view, but showing the piston member at the end of its return stroke, and the valve in position to admit motive fluid to effect the working stroke of said piston. Fig. 4 is a detail side elevation of the valve. Fig. 5 is a sectional view through the valve casing.

Similar reference numerals designate corresponding parts in all the figures of the drawings.

In the embodiment disclosed, a cylinder member 6 is employed having a piston chamber 7, in which a reciprocating piston member 8 operates. A chuck 9 is carried by the front end of the cylinder member, 45 and receives a drill bit 10. A tappet 11 is interposed between the drill bit and the piston. Abutting against the rear end of the cylinder member 6 is a valve casing 11 having a detachable rear wall 12, said rear wall and casing being held in position by a hood 13 surrounding the same and threaded upon the rear end of the cylinder, said hood having an internal shoulder 13^a abutting against the rear wall. The hood in the form of construction shown, has a motive fluid chamber

14 arranged in rear of the wall 12 and a motive fluid supply conduit 15 communicates therewith. The valve casing 11 has in its front end a combined motive fluid supply and exhaust conduit or passage 16, 60 and has in its rear portion and in one or more of its side walls, lateral exhaust ports 17, which communicate with an annular chamber 18 formed between the hood 13 and the valve casing. Leading from this chamber are rearwardly extending exhaust passages 19 that open through the rear end of the hood or head 13, and thus discharge the exhaust air or motive fluid rearwardly and longitudinally of the drill as hereinafter explained.

The front portion of the valve casing is provided with an annular internal groove 20 disposed just in rear of the inlet and exhaust passage 16, and a seat 21 is formed 75 between said groove and said passage. A second annular internal groove 22 is formed within the valve casing in rear of the groove 20, and a third groove or chamber 23 is provided in rear of the groove 22, 80 said groove or chamber 23 being of considerably greater width than the other grooves. A motive fluid supply conduit 24 leads from the chamber 14, through the rear wall 12 and valve casing, and communicates with 85 the annular groove 20. A combined supply and exhaust conduit 25 leads from the annular groove 20, through the front portion of the valve casing, and extends longitudinally through the wall of the cylinder 90 member, communicating, as illustrated at 26 in Fig. 1, with the front portion of the piston chamber 7 in advance of the piston 8.

An automatic reciprocating valve 27 operates in the valve casing, its front end being movable against the seat 21, as shown in Fig. 2, its rear end being movable to a position against the rear wall 12. This valve is provided on its front portion with an annular rib 28, forming a front pressure 95 surface 29 against which the motive fluid supplied to the channel 20 through the passage 24, always acts. The rib 28 also has in the opposite sides of its rear portions semi-circular pockets 28^a. The said valve is 100 provided with a second peripheral rib 30 that moves into register with the internal rib, formed between the grooves 22 and 23 of the valve casing, said rib 30 also moving to a position between the side walls of the 105 110

rear groove 23, as illustrated in Fig. 3. The valve 27 furthermore has on its rear end a peripheral rib 31 that operates snugly in the groove or chamber 23, and has a rear pressure surface 32 of greater area than the pressure surface 29. Finally, the valve 27 is provided with an exhaust passage 33 that opens through both ends of the same, the front and inlet end of said exhaust passage being always in alinement with the combined inlet and exhaust passage 16, and its rear end being movable into and out of coaction with a closure plug 34 formed upon the rear wall 12. This plug is surrounded by a valve seat 35, into and out of coaction with which the rear end of the valve moves. When in coaction with such valve as shown in Fig. 3, communication between the exhaust passage 33 and the exhaust port 17 of the valve casing, is cut off. At the same time, the rear pressure surface of the valve 32 is still exposed in the chamber or groove 23, as shown in Fig. 3, while communication between said chamber and the exhaust channel 33 through the valve is cut off.

Leading to the rear end of the chamber or groove 23 is a conduit 36, said conduit having an inlet port, 37 opening into the piston chamber 7 at a point that will insure its being covered and uncovered by the piston during the reciprocation of the latter. A vent port 38 is preferably employed that communicates with the groove or chamber 23, and with the exhaust chamber 18 said port being covered and uncovered by the rib 31 and permitting the escape of any leakage that may occur. The piston 8, as shown, is provided at its rear end with a closure plug 39, and this plug is so arranged that it will pass through the combined inlet and exhaust passage 16 and snugly enter the front end of the exhaust passage 33 through the valve. It will be observed that the diameter of the closure plug 39 is less than the diameter of the passage 16.

The operation of the structure is substantially as follows. Assuming the parts in the position illustrated in Fig. 3, it will be evident that motive fluid, under pressure, will be in the annular groove 20, which at all times is in communication with the supply conduit 15 through the conduit 24. The motive fluid flows from the groove 20 through the combined supply and exhaust port 16 into the piston chamber 7 in rear of the piston, thus effecting the forward or working stroke of said piston. The necessary exhaust from the chamber 7 in advance of the piston takes place through the port 26, the conduit 25, the port 17, chamber 18, and ports 19, as will be obvious. When the valve is in this position, as shown in Fig. 3, the exhaust passage 33 through said valve is closed by the plug 34 and valve seat 25, but

the rear pressure surface 32 is exposed so that when the piston 8 in its forward movement uncovers the port 37 of the conduit 36, motive fluid under pressure will flow through said conduit and act against the rear pressure surface 32. This surface is of greater area than the front surface 29 and the pressure will effect a forward movement of the valve until the front end of said valve engages the seat 21. As a consequence, the flow of motive fluid from the groove 20 through the passage 16 will be cut off, as shown in Fig. 2, while the exhaust passage 33 through the valve will not only be in communication with the piston chamber 7 in rear of said piston, but its rear end will now be opened and will be in communication with the exhaust port 17 of the valve casing. At the same time, the pockets 28 come into communication with the groove 20, thus permitting motive fluid to flow from said groove through the pockets into the conduit 25, which leads said motive fluid into the front end of the piston chamber in advance of the piston. The said piston therefore begins its return movement, and the pressure of the exhaust passing through the passages 16 and 33 will be sufficient against the rear pressure surface 32 to hold the valve in its foremost position against the pressure of the motive fluid, acting upon the front pressure surface 29. The valve therefore maintains its foremost position until the plug closure 39 of the piston passes through the port 16, and enters the exhaust passage 33. Immediately the exhaust through said passage is cut off, and consequently the pressure of the exhaust against the surface 32 is immediately reduced. Therefore the pressure of the motive fluid against the front pressure surface 29 overcomes the reduced pressure against the rear surface 32, and forces the valve rearwardly. This rearward movement is also assisted by the compression of the exhaust in the chamber 7 which cannot now escape through the passage 33 because of the closure of said passage by the plug 39. An air cushion is consequently formed, which acts against the front end surface of the valve, and adds its pressure to that of the motive fluid against the pressure surface 29. The valve is now in its rearmost position again, as illustrated in Fig. 3, and the operation above described is again repeated.

In connection with this structure, it is to be noted that while the direct pressure of motive fluid from the piston chamber 7 through the conduit 36 effects the forward movement of the valve, it is the exhaust pressure against the rear surface 32 that maintains the valve in its forward position, and furthermore it is the reduction of the exhaust pressure that permits the motive fluid pressure against the front pressure sur-

face 29 to move the valve rearwardly, assisted by the compression of the exhaust in the rear end of the piston chamber 7, after the exhaust passage 33 is closed by the plug 39. It is also to be noted that the exhaust from the instrument is discharged longitudinally and rearwardly through the ports 19. This is a decided advantage, particularly in drilling machines, as it avoids to a very material degree the raising of dust that is necessarily incident to the operation of drilling machines.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new, and desire to secure by Letters Patent, is:—

1. In an instrument of the character described, the combination with a cylinder member, of a piston operating therein, and means for controlling the supply of motive fluid to and its exhaust from the cylinder member, said means including a movable valve having an exhaust passage that opens through both ends thereof and a stationary closure plug for one of the open ends, said valve being movable into and out of coaction with said plug.

2. In an instrument of the character set forth, the combination with a cylinder member, of a piston operating in the cylinder member, a valve casing having a valve chamber, an inlet and exhaust conduit for the cylinder member communicating with one end of the valve chamber, and a valve operating in the chamber and having an internal exhaust passage provided with an inlet that opens through the end of the valve and communicates with the end of the chamber with which the conduit communicates.

3. In an instrument of the character set forth, the combination with a cylinder member having a piston chamber, of a piston operating in the chamber, a valve casing having a valve chamber, a combined inlet and exhaust conduit leading from the valve chamber to the piston chamber and constituting means for supplying motive fluid to the cylinder member to effect the working stroke of the piston, a valve operating in the valve chamber and controlling the admission and exhaust conduit, said valve having an exhaust passage therethrough and being provided with pressure surfaces of different areas against the smaller of which the motive fluid continuously operates to urge

the valve in one direction, means for closing the exhaust when the valve has been moved to a predetermined position by the motive fluid acting against the smaller area, and a second conduit leading from the cylinder member for conveying therefrom a portion of the motive fluid utilized in effecting the working stroke of the piston and directing such motive fluid against the surface of greater area of the valve to move said valve in a direction opposed by the pressure against the smaller area to cut off the supply for the admission and exhaust conduit, said second conduit being covered and uncovered by the piston during its movement and when uncovered being in direct communication through the piston chamber with the admission and exhaust conduit.

4. In an instrument of the character set forth, the combination with a cylinder member and a piston member operating therein, of means for controlling the supply of motive fluid to and its exhaust from the cylinder member, said means including a valve having an exhaust passage that opens through both of its ends, and a closure for one of said ends, the said valve being movable into and out of coaction with the closure, the piston member constituting a closure for the other end and being movable into and out of coaction therewith.

5. In an instrument of the character set forth, the combination with a cylinder member and a piston member operating therein, of means for controlling the supply of motive fluid to and its exhaust from the cylinder member, said means including a valve having an exhaust passage that opens through both of its ends, and a stationary closure plug for one of said ends, said valve being movable into and out of coaction with the closure plug, the piston member having a reduced plug constituting a closure for the other end and being movable into and out of said end.

6. In an instrument of the character set forth, the combination with a cylinder member and a piston member operating therein, of means for controlling the supply of motive fluid to and its exhaust from the cylinder member, said means including a valve having an exhaust passage provided with an inlet opening through one end of the valve, and a discharge opening through the opposite end, and a stationary closure for the discharge end, said valve being movable into and out of coaction with the closure, the piston member constituting a closure for the inlet end of the exhaust passage and being movable into and out of coaction therewith.

7. In an instrument of the character set forth, the combination with a valve casing having an exhaust port at its rear end, of a reciprocating valve operating in the casing

and having an exhaust passage, the discharge end of which opens through the rear end of said valve, a rear wall for the valve casing having a valve seat, the valve being movable into coaction with the seat to cut off communication between the discharge end of the exhaust passage and the exhaust port and being movable away from said seat to open said communication, a cylinder member, and a piston member operating in the cylinder member and having its movements controlled by the valve.

8. In an instrument of the character set forth, the combination with a valve casing having an exhaust port at its rear end and also having a rear wall provided with a plug, of a reciprocatory valve operating in the casing and having an exhaust passage, the discharge end of which opens through the rear end of said valve and receives and is closed by said plug, the valve being movable away from the plug to establish communication between the exhaust passage and the exhaust port, a cylinder member arranged in advance of the valve casing and having open communication therewith, and a piston member operating in the cylinder member and having a reduced plug at its rear end that moves into and out of the valve.

9. In an instrument of the character set forth, the combination with a valve casing having an exhaust port at its rear end, of a reciprocatory valve operating in the casing and having an exhaust passage, the discharge end of which opens through the rear end of said valve, a rear wall for the valve casing having a valve seat, the valve being movable into coaction with the seat to cut off communication between the discharge end of the exhaust passage and the exhaust port and being movable away from said seat to open said communication, a cylinder member, a piston member operating in the cylinder member and having its movements controlled by the valve, and means for introducing motive fluid behind the valve when the exhaust passage therethrough is closed by the valve seat and when the piston member is in a predetermined position.

10. In an instrument of the character set forth, the combination with a valve casing having an exhaust port at its rear end, of a reciprocatory valve operating in the casing and having an exhaust passage, the discharge end of which opens through the rear end of said valve, a rear wall for the valve casing having a valve seat, the valve being movable into coaction with the seat to cut off communication between the discharge end of the exhaust passage and the exhaust port and being movable away from said seat to open said communication, a cylinder member, a piston member operating in the cylinder member and having its movements

controlled by the valve, and a motive fluid conduit leading from the cylinder member to the valve casing in rear of the valve, said conduit being covered and uncovered by the piston member.

11. In an instrument of the character set forth, the combination with a valve casing having a lateral exhaust port at its rear end, of a reciprocatory valve operating in the casing and having an exhaust passage that opens through both ends, a rear wall for the valve casing having a valve seat, the valve being movable into coaction with the seat to cut off communication between the discharge end of the exhaust passage and the exhaust port and being movable away from said seat to open such communication, a cylinder member, a piston member operating in the cylinder member and having a reduced end that is movable into the exhaust passage of the valve, and a motive fluid conduit leading from the cylinder member to the valve casing in rear of the valve, said conduit being covered and uncovered by the piston member.

12. In an instrument of the character set forth, the combination with a cylinder member and a piston member operating therein, of a reciprocatory controlling valve having oppositely disposed pressure surfaces of different areas and also having an exhaust passage, means for introducing motive fluid into the cylinder member and maintaining the same against the pressure surface of less area, means for conducting the exhaust from the cylinder member and carrying it against the opposite surface of greater area to maintain the valve in a predetermined position and against movement by the motive fluid pressure against the smaller surface during the exhaust period, and means that moves with the piston member and closes the exhaust passage in the valve to stop the exhaust and thus relieve the surface of greater area of said exhaust pressure.

13. In an instrument of the character set forth, the combination with a cylinder member and a piston member operating therein, of a reciprocatory controlling valve having a front pressure surface and a rear pressure surface of greater area than the front surface, said valve having an exhaust passage, means for introducing motive fluid into the cylinder member and maintaining the same against the front pressure surface, means for conducting the exhaust from the cylinder member and carrying it against the rear surface to maintain the valve in the predetermined position and against movement by the motive fluid pressure against the front surface, and means carried by the piston and entering the exhaust passage for stopping the exhaust and thus relieving the surface of greater area of such exhaust pressure.

14. In an instrument of the character set

- forth, the combination with a cylinder member and a piston member, of a reciprocatory valve having an exhaust passage opening through both ends, said valve having an annular front pressure surface and having a rear pressure surface at its rear end surrounding the exhaust passage and of greater area than the front surface, means for conducting motive fluid to the cylinder member and maintaining it against the front pressure surface, a rear valve seat into and out of coaction with which the rear end of the valve moves to respectively close and open the exhaust passage therethrough, 15 means for conducting motive fluid against the rear surface when the passage is so closed, and means for maintaining a pressure from the exhaust against the rear surface when the exhaust passage is opened.
- 20 15. In an instrument of the character set forth, the combination with a cylinder member, of a reciprocatory piston therein, a valve casing located at the rear end of the cylinder member and having an open combined supply and exhaust conduit, a rear wall for said valve casing having a valve seat, a reciprocatory valve operating in the valve casing and having an exhaust passage opening through both ends, one end of said exhaust 25 passage being closed and opened by the valve seat, a closure carried by the piston and movable into and out of the other end of the exhaust passage, said valve having its front portion provided with an annular pressure surface and having its rear end provided with an opposite pressure surface of greater area than the front surface, means for directing motive fluid to the cylinder member and maintaining it against the front 30 pressure surface, a conduit leading from the cylinder member to the rear portion of the valve casing and directing motive fluid against the rear surface of greater area, said conduit being covered and uncovered by the 35 piston, and means communicating with the rear end of the valve casing for carrying off the exhaust.
- 40 16. In an instrument of the character set forth, the combination with a valve casing
- having a combined supply and exhaust passage at one end, the other end being closed and having a plug projecting longitudinally thereinto, said casing also having a motive fluid inlet port in one side between its ends, of an automatic reciprocatory valve operating in the casing and having an exhaust passage extending longitudinally therethrough and opening through both ends thereof, one end of the exhaust passage of the valve being always in communication 60 with the combined supply and exhaust passage of the valve casing, the other end being closed and opened by the plug upon the reciprocation of the valve.
- 45 17. In an instrument of the character set forth, the combination with a valve casing having an exhaust port, of a valve having a front pressure surface and a rear pressure surface of greater area than the front pressure surface, said valve also having an exhaust passage therethrough that conducts the exhaust against the rear pressure surface, a cylinder member and a piston member operating in the cylinder member, means for leading motive fluid to the valve casing 75 and maintaining it at all times against the front pressure surface, means covered and uncovered by the piston member for conducting motive fluid from the cylinder member to the rear pressure surface, a valve seat 80 carried by the rear casing wall to close the exhaust passage of the valve and cut off communication between the same and the rear pressure surface, and a plug carried by the piston member and entering the front 85 end of the exhaust passage to close the same and thus reduce the exhaust pressure against the rear pressure surface when the valve is unseated, forming an air cushion that acts with the motive fluid against the front pressure surface of the valve to force the valve rearwardly.

In testimony whereof I affix my signature in presence of two witnesses.

DANIEL S. WAUGH.
